Patented June 5, 1917.

2 SHEETS—SHEET 2.

UNITED STATES PATENT OFFICE.

ALONZO BLEVINS, CHARLES F. KILGORE, AND ALLEN L. BLEVINS, OF COEBURN, VIRGINIA, ASSIGNEES, BY DIRECT AND MESME ASSIGNMENTS, OF ONE-FOURTH TO SAID ALONZO BLEVINS AND ONE-FOURTH TO SAID KILGORE, AND ONE-FOURTH TO MASON L. JOHNSON AND ONE-FOURTH TO JOSEPH J. BODY, BOTH OF DANTE, VIRGINIA.

MINE-DOOR.

1,228,643.

Specification of Letters Patent.

Patented June 5, 1917.

Application filed April 20, 1916. Serial No. 92,478.

To all whom it may concern:

Be it known that we, ALONZO BLEVINS, CHARLES F. KILGORE, and ALLEN L. BLEVINS, citizens of the United States, residing at 5 Coeburn, in the county of Wise and State of Virginia, have invented certain new and useful Improvements in Mine-Doors; and we do declare the following to be a full, clear, and exact description of the invention, 10 such as will enable others skilled in the art to which it appertains to make and use the same.

Our invention relates to improvements in mine doors of the type which are normally 15 closed and opened automatically by the passage of mine cars over the track in the tunnel across which the door is positioned.

The object of the invention is to provide 20 efficient means for operating the door without employing a multiplicity of complicated parts.

With this general object in view, the invention resides in certain novel features of construction and in unique combinations of parts to be hereinafter fully described and claimed, the descriptive matter being supplemented by the accompanying drawings which constitute a part of this application and in which:

30 Figure 1 is a top plan view of the invention with the door and its frame in horizontal section;

Fig. 2 is a side elevation showing the door frame in section;

35 Fig. 3 is a vertical transverse section taken on the plane indicated by the line 3—3 of Fig. 2;

Fig. 4 is an enlarged section showing the manner in which the car wheels operate the 40 depressible rails;

Fig. 5 is a detail vertical section showing more particularly the mounting of the main operating gears of the door; and

45 Fig. 6 is a detail longitudinal section through one of the depressible rails taken on the plane indicated by the line 6—6 of Fig. 1.

In specifically describing the construction shown in the drawings above briefly 50 described, similar characters will be placed on corresponding parts throughout the several views and reference will be herein made to the numerous elements by their respec-

tive indices. To this end, the numerals 1 designate the parallel rails of an ordinary 55 mine track, said track extending through a door frame 2 which is suitably secured in a tunnel or the like 3. A pair of upright shafts 4 extend between the upper and lower ends of the frame 2 and are rotatably mounted in appropriate bearings, said shafts carrying the two sections 5 of the door, which sections are normally disposed as shown in Figs. 1 and 3. The shafts 4 are provided with beveled pinions 6 meshing with comparatively large beveled gears 7 which are mounted on bolts or the like 8 extending through spacing sleeves 9 and through the sides of the door frame.

Horizontal longitudinally disposed links 70

10 are pivoted to the gears 7 above the centers thereof, said links extending in opposite directions from the frame 2 and being pivoted at their other ends to the upper ends of rigid crank arms 11 which are se-

25 cured to and rise from the opposite ends of crank shafts 12, said ends being mounted rockably in appropriate bearings 13 preferably secured to the rails 1. The cranks

14 of the shafts 12 are preferably formed by 80 bowing the central portions of said shafts upwardly between said rails 1, these cranks

being normally inclined as shown by the dotted lines in Fig. 2 and supporting thereon the intermediate sections 15 of a pair of 85 depressible rails, these rails being preferably constructed of angle metal as shown. The sections 15 are connected at intervals by transverse bars 15^a riveted or otherwise secured thereto.

90 Slotted plates 16 are secured to and project beyond the ends of the rail sections 15, said plates supporting thereon the inner ends of the end sections 17 of said depressible rails, said ends having headed studs or the like 18 passing through the slots 19 of the

95 plates 16, whereby sliding and pivotal connections are established at these points. The outer ends of the sections 17 are pivoted at 20 to the rails 1. The intermediate sections 100

15 of the depressible rails as well as the inner portions of the sections 17 thereof are normally raised above the rails 1 by coiled springs 21 disposed beneath the ends of said sections 15, whereby said rails will be always 105 properly positioned to be operated by the

passage of a mine car thereover. The cranks 14 are held in operative relation in respect to the depressible rails by the tension of coiled springs 22 connected at one end to the 5 crank arms 11 while their other ends are anchored by any suitable means such as rods 23 having turnbuckles 24 for varying the tension of the springs 22. As shown most clearly in Fig. 2 the springs 22 also serve to 10 hold the gears 7 normally in proper position to retain the door closed, said springs also exerting their tension to close said door when opened.

By constructing the invention in the manner shown and described, the passage of a mine car upon the depressible rails consisting of the sections 15 and 17, will depress said rails from the position shown in Fig. 3 to that depicted in Fig. 4. The result or 15 this movement is that the shafts 12 are rocked by the cranks 14, this movement causing the crank arms 11 to so operate the links 10 as to turn the main operating gears 7, the latter now transferring motion to the door sections 5 through the instrumentality of 20 the pinions 6. This opens the door and allows the car to pass therethrough and when said car has left the depressible rails and again travels onto the rails 1, the 25 springs 21 and 22 will return all parts to their normal positions. It is to be observed that both cranks 14 incline upwardly toward the doors 5 and contact with the rails 15 at 30 points spaced between the rock shafts 12 and said doors. This structure or an equivalent arrangement is an important feature since 35 a car approaching the doors in either direction will open said doors in the direction in which said car is traveling as indicated by 40 the arrows in Fig. 1. By this arrangement, therefore, economy in space is had and the depressible rails need not be of such length as would be necessary if the doors 5 opened 45 toward an approaching car. It is also to be noted that when one crank 14 moves downwardly by the weight of a car traveling onto the adjacent end of the rails 15, the other crank must move upwardly to a slight extent due to the inclination of said cranks. 50 This operation is readily permitted, however, by the combined pivotal and sliding connections between the parts 15 and 17, said connections consisting of the slotted plates

16 and the headed studs 18 shown most clearly in Fig. 6.

55

From the foregoing, taken in connection with the accompanying drawings, the construction, manner of operation and advantages of the invention will be readily understood without requiring a more extended explanation. In conclusion, however, we will state that although certain specific details have been shown and described for accomplishing probably the best results, numerous changes may be made within the scope of the invention as claimed without sacrificing the main advantages thereof. Furthermore, although we have shown and described our invention as employed in connection with mines, it is to be understood that it may be 60 used wherever applicable.

65

70

We claim:

The combination with a railway and a door mounted to swing across the same, a pair of operating links extending to opposite 75 sides of said door, operating connections between said door and links for opening the former in either direction according to the direction in which the links are shifted, a depressible rail passing beneath the door and disposed adjacent one rail of the railway, inclined rail sections at and in line with the ends of said depressible rail, said sections being both pivotally and slidably connected with the ends of said depressible rail and 80 being pivoted to said one rail of the railway, and a pair of rock shafts extending transversely of the railway on opposite sides of 85 the door, said shafts having upstanding crank arms pivoted to the aforesaid links and additional cranks upon which the depressible rail rests, said rail bearing on said 90 additional cranks at points spaced toward the door from said rock shafts whereby a car traveling in either direction will open the door in the direction said car is traveling.
